M. W. EDWARDS

SAW STRETCHER ATTACHMENT

Filed July 12, 1923

Patented Mar. 10, 1925.

1,529,120

UNITED STATES PATENT OFFICE.

MATTHEW WARD EDWARDS, OF ALBION, CALIFORNIA.

SAW-STRETCHER ATTACHMENT.

Application filed July 12, 1923. Serial No. 651,152.

To all whom it may concern:

Be it known that I, MATTHEW WARD EDWARDS, a citizen of the United States, and a resident of Albion, county of Mendocino, State of California, have invented a new and useful Saw-Stretcher Attachment, of which the following is a specification.

The present invention relates to improvements in saw stretching machines, and its particular object is to provide an attachment for a saw stretching machine that will allow saws, particularly band saws that have been dished or otherwise curved in the operation of the same, to be straightened. It is particularly proposed to provide an attachment of this character that can be conveniently used in connection with an up to date saw stretching machine. The most modern machines of this character are provided with two rollers adapted to cooperate in engaging the saw blade and in advancing the same, the two rollers being mounted with freedom of axial sliding motion so that they can successively engage successive portions of the saw without requiring any shifting of the latter. The machine is further provided with means for adjusting the upper roller for affecting a tight engagement between the two rollers and the saw blade. The particular object of the present invention is to provide an attachment of the character described that can be readily used in connection with the lower roller as well as with the upper roller so that it may be moved to suit the requirements of the case without necessitating the removal of the saw. Further objects and advantages of my device will appear as the specification proceeds.

The preferred form of the invention is illustrated in the accompanying drawing in which Figure 1 shows a perspective view of a modern saw stretching machine having my device attached thereto; Figure 2 a front view of my device with the position of certain elements of the machine shown in dotted lines; Figure 3 an enlarged plan view of my device; Figure 4 a sectional view taken along line IV-IV of Figure 3; Figure 5 a plan view of a ring adapted to be used for holding my device in an operative position when used in connection with the upper roller; Figure 6 a section taken along line VI-VI of Figure 5; Figure 7 an enlarged detail view of an eye bolt used in my device; Figure 8 a section through the machine taken along line VIII-VIII of Figure 1; and

Figure 9 a view of a spring used in the device. While I have shown only the preferred form of the invention, it should be understood that various changes or modifications may be made within the scope of the claims hereto attached without departing from the spirit of the invention.

The saw stretching machine (1) shown in perspective view in Figure 1 is of standard make and comprises a pedestal (2) a base plate (3) resting thereon having two standards (4) rising therefrom, a cross beam (6) pivoted to the standards as shown at (7), a latch bar (8) engaging the cross beam as shown at (9) for holding the same in a horizontal position, and a head (11) slidable in the cross beam. As may be seen from Figure 8 a casting (12) supporting two bearings (13) is adapted to be moved vertically by means of a threaded member (14) passing through the head (11) and engaging a recess (16) in the casting. A handle (17) is provided for rotating the threaded member (14). In the two bearings (13) is supported a shaft (18) which latter carries between the two bearings a roll (19). It will be seen that due to this construction the roll (19) may be raised and lowered by turning the handle (17) and is also capable of axial motion by sliding the head (11) on the cross beam (6). A lower roller (21) is provided between two bearings (22) on a shaft (23) receiving rotary motion from a pinion (24). The two bearings (22) are slidable in the base by means not shown in the drawing.

My invention consists principally in the member (26) shown in detail in Figures 3 and 4, and comprising two arched bars (27) and two cross members (28) engaging the ends of the bars and holding the same in spaced relation. From the center of each end member (28) extends a projection (29), the function of which will be explained later.

To use my device in connection with the lower roll it is only necessary to place the member (26) on the two bearings (22) in such a manner that the two arched bars (27) straddle the lower roll (21) and project beyond the same so that when the blade of the saw is engaged by the two rollers, the two arched bars (27) will force adjacent parts of the saw blade out of the plane of engagement. Assuming, therefore, that the saw (31) to be stretched has become dished as illustrated in Figure 2, it will be placed on

the two arched members (27) in the manner shown in said figure, and the upper roll will then be forced down upon the lower roll whereupon the saw blade is advanced by 5 the rotation of the two rolls and at the same time straightened out, because the two arched bars keep the adjacent parts of the saw at a higher elevation than the part engaged between the two rollers.

10 While in connection with the lower saw it is only necessary to lay my device on the two bearings, a different method has to be used when my device is to cooperate with the upper roller. For this purpose I provide the 15 ring (32) adapted to be placed around the top of the head (11). The ring is provided with lateral lips (33) extending outwardly, one of them having a perforation (34) therethrough, while the other is slotted as shown 20 at (36). Two springs (37), one of which is shown in detail in Figure 9, terminating in rings (38) are adapted to engage with one end of the notches (39) in the projections (29) of the member (26), and are secured 25 with their other end to eye bolts (41), one of which is shown in Figure 7. One of the eye bolts is passed through the perforation (34) in one of the lips of the ring (32) and held in place by means of a wing nut (42), 30 while the other eye bolt is engaged with the slot (36) of the ring (32) and also held in place by means of a wing nut.

To attach my device for use in connection 35 with the upper roller the two arched bars (27) are placed to straddle the said roller, one of the springs is engaged with the notch (39) of one of the projections (29), while its eye bolt is extended through the perforation (34) of the lip (33) and secured by means of 40 the wing nut (42) and the other spring (37) is secured to the other projection (29) of the member (26) and its eyebolt slipped into the slot (36) to be held by the wing nut (42). The tension of the two springs (37) may be 45 adjusted by tightening or loosening the wing nuts (42). It will be seen that in this manner the member (26) is firmly held in place so as to straddle the upper roller (19) and to force adjacent parts of the saw out of the 50 plane of that portion engaged by the rollers while at the same time it is elastic and does not interfere with the raising and lowering of the upper roller nor with an axial adjustment of the same.

55 I claim:

1. In combination with a saw strteching machine having a lower roller, an upper roller cooperating therewith for advancing the saw by engaging an intermediate portion 60 thereof and a cross beam with a head slid- able thereon supporting the upper roller, a member formed to straddle the active portion of the upper roller having elements pro- jecting beyond the said roller on opposite 65 sides thereof for forcing adjacent portions

of the saw out of the plane of engagement and means engaging the head so as to be movable with the same for supporting the said member.

2. In combination with a saw stretching 70 machine having a lower roller, an upper roller cooperating therewith for advancing the saw by engaging an intermediate portion thereof and a cross beam with a head 75 slid- able thereon supporting the upper roller, a member formed to straddle the active portion of the upper roller having elements pro- jecting beyond the said roller on opposite 80 sides thereof for forcing adjacent portions of the saw out of the plane of engagement and means engaging the head for supporting 85 the said member, comprising a ring adapted to be placed over the head and an operative connection between the ring and the strad- dling member.

3. In combination with a saw stretching machine having a lower roller, an upper roller cooperating therewith for advancing the saw by engaging an intermediate portion 90 thereof and a cross beam with a head slid- able thereon supporting the upper roller, a member formed to straddle the active portion of the upper roller having elements pro- jecting beyond the said roller on opposite 95 sides thereof for forcing adjacent portion of the saw out of the plane of engagement and means engaging the head for supporting the said member, comprising a ring adapted to be placed over the head having two lips 100 extending therefrom in opposite direction, two registering projections on the straddling member and operative connections between the lips and the projections.

4. In combination with a saw stretching machine having a lower roller, an upper 105 roller cooperating therewith for advancing the saw by engaging an intermediate portion thereof and a cross beam with a head slid- able thereon supporting the upper roller with freedom of vertical adjustability, a 110 member formed to straddle the active portion of the upper roller having elements pro- jecting beyond the said roller on opposite 115 sides thereof for forcing adjacent portions of the saw out of the plane of engagement and yielding means engaging the head for supporting the said member.

5. In combination with a saw stretching machine having a lower roller, an upper roller cooperating therewith for advancing 120 the saw by engaging an intermediate portion thereof and a cross beam with a head slid- able thereon supporting the upper roller with freedom of vertical adjustability, a 125 member formed to straddle the active portion of the upper roller having elements pro- jecting beyond the said roller on opposite sides thereof for forcing adjacent portions of the saw out of the plane of engagement and yielding means engaging the head for 130

supporting the said member, comprising a ring adapted to be placed over the head and a spring connection between the ring and the straddling member.

- 5 6. In combination with a saw stretching machine having a lower roller, an upper roller cooperating therewith for advancing the saw by engaging an intermediate portion thereof and a cross beam with a head slid-
10 able thereon supporting the upper roller with freedom of vertical adjustability, a member formed to straddle the active portion of the

upper roller having elements projecting beyond the said roller on opposite sides thereof for forcing adjacent portions of the saw out 15 of the plane of engagement and yielding means engaging the head for supporting the said member, comprising a ring adapted to be placed over the head having two lips ex-
tending therefrom in opposite direction, two 20 registering projections on the straddling member and spring connections between the lips and the projections.

MATTHEW WARD EDWARDS.
